CLAIM

The ornamental design for a toe stretcher, as shown and described.

DESCRIPTION

FIG. 1 is a front view of the toe stretcher of my invention;
FIG. 2 is a top plan view of the toe stretcher;
FIG. 3 is a bottom plan view of the toe stretcher;
FIG. 4 is a left side view of the toe stretcher;
FIG. 5 is a right side view of the toe stretcher;
FIG. 6 is a cross-sectional view taken along line 6—6 in
FIG. 2; and,
FIG. 7 is a front view of the toe stretcher in use.
The broken line showing the human form is for illustrative
purposes only and forms no part of the claimed design.
